UNITED STATES PATENT OFFICE.

OTTO E. SMITH, OF JANEVILLE, WISCONSIN.

WASHING-MACHINE.

SPECIFICATION forming part of Letters Patent No. 327,832, dated October 6, 1885.

Application filed January 28, 1885. Serial No. 154,208. (No model.)

To all whom it may concern:

Be it known that I, OTTO E. SMITH, of Janesville, in the county of Rock, and in the State of Wisconsin, have invented certain new and useful Improvements in Washing-Machines; and I do hereby declare that the following is a full, clear, and exact description thereof.

My invention relates to washing-machines; and it consists in certain peculiarities of construction, all as will be more fully set forth hereinafter.

In the drawings, Figure 1 is a side elevation of the device. Fig. 2 is a longitudinal vertical section thereof, taken through the center of the machine, and looking from the side opposite to that shown in Fig. 1. Fig. 3 is an end view, partly in section, on the line xx of Fig. 2. Figs. 4, 5, 6, 7 and 8 are detail views, drawn to an enlarged scale, illustrating the construction of the several parts shown more clearly.

A is the wash-box, preferably of the form shown, and mounted upon the legs a . The longest or side boards of the box are provided with interior L-shaped grooves, a' a'' , the latter being enlarged at its end, as shown at a^3 , and the former having a central enlargement, a^4 , which grooves are designed for the reception of the ends e of the straps E and the plates F, respectively, which receive the journals of the rollers B C, around which the endless apron D moves, as hereinafter explained.

The straps E are flat strips of metal, one against each side piece of the wash-box, and their upper ends are bent and folded over, so as to form loops e' , which receive the free ends g of coiled springs G, secured at the center of the coil to the said side pieces of the box, as shown at g' . The roller C has journals c at each end, and these project into perforations in the ends e of the straps E, as shown in Fig. 6, while each end of the roller C is fitted with a circular scalloped head, C', the said scallops e' , preferably eight in number, serving to receive the adjacent surfaces of the slats of which the endless apron D is composed, the said apron being sustained at the other end of its play by the scalloped heads B' on the roller B, whose journals b rest in the notches of the plates F within the enlargements a^4 of the

vertical grooves a' in the sides of the wash-box, and on one side the journal b carries a ratchet-wheel, b^2 , rigid therewith, for actuating the said apron D, as hereinafter explained. 55

The apron D is composed of a series of corrugated slats, d, and each slat is substantially octagonal in section, except that the upper or most exposed face is provided with a longitudinal V-shaped notch, d' . Each end of each 60 slat d is notched out also, and a continuous strip, d'' , of leather or other suitable material, such as rubber, cloth, or other fabric, is inserted edgewise into these end notches on each side, and secured therein by brads or fasteners d^3 . 65 so that when the apron is complete and in place it will present on its operative or outer surface a series of corrugations or V-shaped notches, the slats d being far enough apart to permit their inner surfaces to move in and 70 out of the scallops $b' e'$ in the heads B' C' of the rollers B C without binding, and also so as to permit the water or suds to pass freely between them.

H is the rubber, and consists of a suitable 75 metallic frame extending across the entire box and suspended from journals h h' , which turn in suitable boxes or bearings, a^5 a^6 , in the top of the sides of the wash-box. From the lower part of the frame H, below the brace or 80 reach H' thereof, and projecting down from each side, there extends a rounded plate, H', which receives the journals of the corrugated rubbing-rollers h^1 h^2 , four (more or less) in number, and arranged in the arc of a circle. 85

I is a pivoted pawl, having a finger, i, at one end for engagement with the teeth of the ratchet-wheel b^2 , and at the other end having a pin, i' , which may be placed in any one of a series of holes, i^2 i^3 , in the side piece of the frame H, 90 as desired, so as to adjust the limit or "throw" of the pawl I to any number of teeth on the ratchet-wheel b^2 within the scope of the said pawl.

J is a spring-pawl, fastened at j to the side 95 of the wash-box, and its free end being provided with a guard, j' , that slips over the teeth as the ratchet-wheel b^2 is revolved in one direction, and which serves as a stop to prevent the said wheel from turning in the opposite direction.

J' is a button, notched on its lower edge to

keep the spring-pawl J to place, and which button may be moved up or down at will, to diminish or increase the tension of the spring-pawl J.

5 The motive power and its connections will next be described.

K is the main gear-wheel, mounted upon a stud, k, which projects from the outside of one of the side pieces of the wash-box, and the hub 10 of the gear-wheel is squared to receive the crank L. Another stud, m, receives a pinion, M, which meshes with the wheel K, and on the outside of the pinion is a plate, m', projecting beyond the periphery of the said pinion and bearing a crank-pin, m². The journal 15 h' of the rubber frame H extends out beyond the outer side of the wash-box, and is here squared to receive one end of the lever N, whose other end, n, is bifurcated to receive the link O, the adjacent ends of the lever N n and link O being perforated, (with a series of holes, if desired, to secure necessary adjustment in certain cases,) and the parts being united by the bolt or pin n', while the other end of the 20 link O is secured to the crank-pin m² on the link m', attached to the pinion M.

The operation of my device will be readily understood from the foregoing description of its construction. The box being partially 25 filled with the water and soap or "suds," the clothing to be washed is placed upon the endless apron D, and the crank L revolved, which will cause the apron to move continuously forward, carrying the clothing under the rubber H and its rollers h² h², and the said rubber will swing back and forth over the clothing in the arc of a circle, its rollers h² h² meanwhile 30 freely revolving until every particle of dirt is freed from the clothing in a comparatively 35 short time and with but little expenditure of strength. The enlargement a³ in the side grooves of the wash-box, in connection with the springs G, from which the straps E are suspended, enables the apron D to yield and be 40 forced downward to any extent desired, (as when pieces of carpet or other thick goods are 45 being washed,) and yet, owing to the force of said springs G, the apron is always held up against the under surface of the rollers of the swinging rubber frame H, and hence the thinnest 50 lace handkerchief can be washed just as thoroughly as thicker goods, and without the slightest injury to the fabric.

The water can be drawn off from the box 55 after washing by means of a hole supplied with a plug or stop-cock at any suitable point.

The rollers B and C may be square, if desired, or have squared ends, so as to receive the heads B' C' without the necessity of a key 60 or feather, and the former construction is shown in the drawings.

Having thus described my invention, what I claim as new, and desire to secure by Letters Patent, is—

1. In a washing-machine, the combination 65 of the wash-box with an endless slotted apron arranged in the arc of a circle, with one end in a lower horizontal plane than the other end of said apron, the lower end of which is suspended from spring hangers or straps and capable of movement vertically, and a rubbing-frame to be moved back and forth in the arc of a circle over said apron, substantially as set forth. 70

2. In a washing-machine, the combination 75 of the wash-box and swinging rubber with the endless apron D, the roller C, with scalloped heads C', adapted to receive the inner surfaces of the slots of which the apron is composed, and the journals c, the stops E, with ends e, to 80 receive the journals c, and the springs G, from which the said stops are suspended, substantially as set forth.

3. In a washing-machine, the wash-box A, the side pieces whereof are formed with the 85 L-shaped grooves a' a², the latter having an end enlargement, a³, and the former having a central enlargement, a⁴, fitted with a notched plate, F, on each side, in combination with the springs G, straps E e, and endless slotted apron 90 D, provided with the rollers B C, having journals b c, respectively, the former journals resting within the notches in the plates F and the latter journals being received in perforations in the ends e of the straps E, substantially as 95 set forth.

4. In a washing-machine, the combination, with the wash-box and endless apron suspended from spring hangers or straps, with the rubber frame H, suspended from bearings 100 in the top of the box sides and extending across the wash-box and having downward extensions on each side connected by rounded plate H², in which are journaled corrugated rubber-rollers h² h², arranged in the arc of a circle, substantially as set forth. 105

5. In a washing-machine, the combination of the wash-box A, endless slotted apron D, rollers B C, and rubber-frame H, carrying rollers h² h², with the ratchet-wheel b², secured 110 to the journal of the roller B, pawl I, pivoted to the rubber-frame H, spring-pawl J, with tension-button J', and gear-wheel, pinion, link, and lever for communicating revolving motion 115 to the apron D and reciprocating motion to the rubber-frame H, substantially as set forth.

In testimony that I claim the foregoing I have hereunto set my hand, at Janesville, in the county of Rock and State of Wisconsin, in 120 the presence of two witnesses.

OTTO E. SMITH.
